[57] CLAIM

The ornamental design for a transmission filter assembly, as shown and described.

DESCRIPTION

FIG. 1 is a top plan view of a transmission filter assembly embodying my design;

FIG. 2 is a bottom plan view of the transmission filter assembly;

FIG. 3 is a side elevational view of the transmission filter assembly;

FIG. 4 is an elevational view of the side of the transmission filter assembly opposite from that shown in FIG. 3;

FIG. 5 is an end elevational view of the transmission filter assembly;

FIG. 6 is an elevational view of the end of the transmission filter assembly opposite from that shown in FIG. 5;

FIG. 7 is a perspective view of the top of the transmission filter assembly; and,

FIG. 8 is a perspective view of the bottom of the transmission filter assembly.
